C. LUSH.

AUTOMATICALLY OPERATED FARM GATE.

APPLICATION FILED SEPT. 3, 1918.

1,321,832.

Patented Nov. 18, 1919.

UNITED STATES PATENT OFFICE

CHARLES LUSH, OF LONDON, ONTARIO, CANADA.

AUTOMATICALLY-OPERATED FARM-GATE.

1,321,832.

Specification of Letters Patent. Patented Nov. 18, 1919.

Application filed September 3, 1918. Serial No. 252,475.

To all whom it may concern:

Be it known that I, CHARLES LUSH, of the city of London, in the county of Middlesex, in the Province of Ontario, Canada, have invented certain new and useful Improvements in Automatically-Operated Farm-Gates, of which the following is a specification.

My invention relates to improvements in automatically operated farm gates and the object of the invention is to devise a simple operating mechanism for carrying the upper and lower hinge connections out of alinement to allow the gate to swing to either the open or closed position and such a device as may be applied to any iron gate and be easily adjusted to take up sag of either of the posts as hereinafter more particularly explained by the following specification.

Figure 1, is a general perspective view of my gate shown in the closed position, the operating cords being broken away intermediate of their length.

Fig. 2, is a vertical section through the major portion of the operating mechanism.

Fig. 3, is an enlarged perspective detail of those parts of the operating mechanism shown in Fig. 2.

Fig. 4, is a perspective detail of the latch.

Fig. 5, is a perspective detail of the latch pin.

Fig. 6 is a sectional plan view of the mechanism for locking the gate in the open position.

Fig. 7, is a sectional plan of the means for limiting the swinging movement of the gate when the upper hinge is carried out of alinement with the lower hinge.

Fig. 8, is a sectional view through the lower hinge connection.

Fig. 9, is an enlarged sectional detail of one of the locking members shown in Fig. 6.

In the drawings like characters of reference indicate corresponding parts in the various figures.

1 indicates a gate and 2 and 3 the gate posts. 4 indicates the gate supporting bar which is adjustably connected to the gate post 2 by means of the bolts 4^x and 4'. These bolts are substantially the same, an enlarged view being shown in Fig. 2. The bolts 4^x and 4' are secured to the gate post by means of nuts 4² and 4³ bearing against the opposite faces of the posts and to the bar 4 by nuts 4⁴ and 4⁵. The lower end of the bar 4

is provided with an enlargement 4⁶ having a horizontal slot 4⁷ through which the lower bolt 4' extends. The upper bolt 4^x extends through the upper portion of the bar 4, the bar being swung thereon. The upper end of the bar 4 is provided with an extension 4⁸ which is offset toward the post 2 and carries upon its upper end a casing 5. This casing 5 is provided so that the mechanism contained therein will be unaffected by frost in winter time. Within the casing 5 is secured an arc-shaped plate 6 having a face gear 6', the teeth of the gear being only at each end, the center portion 6² and end portion 6³ being plain; that is, without teeth.

4⁹ indicates a rectangular boss extending inwardly toward the gate from the upper end of the bar 4. The upper end of the boss is provided with an orifice 4¹⁰. 7 indicates a shaft journaled at its lower end in the orifice 4¹⁰ and provided at its upper end with a horizontally turned portion 7^x which extends over the face gear 6. Upon the horizontal portion 7^x is swung a dog 8 which normally hangs vertically and which when brought into engagement with the teeth 6⁴, is swung in one direction and when brought into engagement with the teeth 6⁵ is swung in the opposite direction so as to remain in an inclined position in engagement with the teeth. When the dog is carried past the teeth over the portion 6³ it again swings to the vertical position by force of gravity.

9 indicates a bevel pinion secured to the shaft 7. 7' indicates an arm extending from the shaft 7 below the gear 9, the outer end of the arm 7' being provided with a depending portion 7^x forming the upper hinge pin of the gate. 10 indicates the upper hinge member of the gate which is formed in two portions 10^x and 10' which clamp around the vertical bar 1^x of the gate 1, the portions 10² and 10³ forming a receiving orifice for the hinge pin 7^x. From the portions 10² and 10³ extend lugs 10⁴ and 10⁵ for a purpose which will hereinafter appear.

11 indicates a boss extending from the bar 4 in proximity to its lower end, the boss 11 being provided with a socket 11^x. 12 indicates the lower hinge member also secured to the bar 1^x of the gate 1, being suitably clamped thereto, the arm 12^x of the member being provided with a depending portion 12^x having a ball end 12² fitting within the socket 11^x. By this means the lower end of 110

the gate is supported to swing either to one side or the other so that the upper hinge pin may be carried laterally out of alignment with the lower hinge connection.

5 13 indicates a stud extending outwardly from the casing 5. 14 indicates a bevel gear mounted upon the stud 13 in mesh with the pinion 9. 14^x indicates an arm secured to the gear 14 and extending normally in a vertical position upwardly from the gear. 15 and 16 indicate posts which are located on the road side in alignment with the gate post 2 and some considerable distance therefrom. 15^x and 16^x indicate pulleys carried by the 10 posts 15 and 16 in proximity to their upper ends. 17 and 18 indicate cords connected at their inner ends to the arm 14^x and extending at their outer ends over the pulleys 15^x and 16^x. The portions of the cords 17 and 18 depending from the pulleys 15^x and 16^x are provided with weighted pull handles 19 and 20. As the driver of the vehicle passes along the road in the direction of arrow approaching the gate and wishing to pass through the 25 gateway he pulls upon the pull handle 19 swinging the arm 14^x in the direction of arrow and thereby turning the shaft 7 in the direction of arrow carrying the hinge pin 7² around the center formed by the shaft 7 and into the position indicated in Fig. 7, this movement being limited by the lug 10⁵ 30 engaging the face of the rectangular boss 4⁹ in proximity to one edge thereof. By this movement the opposite end of the gate is 35 carried upward so that the latch pin thereof hereinafter described will be carried free of the latch allowing the gate to swing to the open position. As the gate swings to the open position the arm 7 carrying the hinge pin 7² and the lower hinge 1 automatically realine themselves as the gate approaches the open position, the gate being locked in the open position by mechanism which I will hereinafter describe.

45 As the cord 17 is pulled as above described and the shaft 7 turned the dog 8 carried by the upper end of the shaft is swung in a position to engage with the teeth 6⁵ thereby holding the mechanism in the position to 50 which it is moved and overcoming the necessity of the operator keeping hold of the rope after it has once been pulled far enough. By this means as soon as the cord has been pulled so as to cause the dog 8 to engage the 55 teeth 6⁵ the gate will automatically swing open enabling the driver to drive on while the gate swings to the open position. It will be understood that the latch pin is not carried free of the latch until the dog has engaged with the teeth 6⁵. If the latch pin were carried free of the latch before the dog would engage the catch would start to open before the dog caught and under these conditions the gate might not swing to the full 60 open position when the operator had re-

leased the cord 17. As soon, however, as the dog catches with the teeth and is locked the gate starts to open insuring that it opens to the full extent to enable the driver to pass through. As the gate hinges realine 70 themselves as the gate arrives at the swung position the dog 8 is given a further circumferential movement carrying it past the teeth 6⁵ and allowing it to swing to a free vertical position ready for movement in the opposite 75 direction.

As before stated the swinging movement of the gate is limited by the lug 10⁵ engaging the boss 4⁹ thereby preventing any danger of the operator pulling the cord 17 too 80 far. When the driver has passed through the gate and reaches the post 16 he pulls upon the pull handle 20 thereby reversing the swinging movement of the shaft 7 so as to carry the upper hinge pin in the opposite 85 direction and cause the gate to swing to the closed position, the swinging movement of the gate at the upper hinge pin being also limited by the lug 10⁴ engaging the adjacent side face of the boss 4⁹. It will, of 90 course, be understood that when the driver is passing in the opposite direction when the gate is opened the lug 10⁴ will engage the front face of the boss 4⁹ and when the gate is being closed the lug 10⁵ engages the 95 corresponding side face of the boss 4⁹ thereby also limiting the swinging movement when the driver is driving in the opposite direction.

In order to prevent the upward swing of 100 the gate as it comes to the closed position caused by the driver accidentally pulling the rope too far just before the gate closes to cause the gate to lift over the latch or cause the dog 8 to reengage with the teeth I have 105 provided a vertical rib 4¹¹ extending from the outer face of the boss 4⁹.

I will now describe my latch and latch pin co-acting with the mechanism hereinbefore 110 described.

21 indicates a plate preferably shield shape. The plate 21 is secured to the post 3 by means of bolts 21^x and 21', these bolts extending through the gate posts and being secured by nuts in a similar way to that employed for securing the bar 4 to the gate post 2. By this means either the upper or lower portion of the plate may be adjusted to or from the gate post so as to realine the plate vertically should the gate post 3 sag 115 120 out of the vertical.

22 and 23 indicate pins extending from the plate 21 in proximity to each side thereof. 24 indicates a plate extending outwardly from the main plate 21 in proximity to the bottom thereof. 25 and 26 indicate swinging catches each comprising a vertical portion 26^x and an inwardly inclined portion 26', which rests at its lower edge upon the plate 24 in proximity to the center thereof. 125 130

The inner face of each vertical portion 26* is provided with notches 26² which are graduated in length.

Although I have only shown two of these notches it will, of course, be understood that any number might be employed.

27 indicates a vertical plate also extending from the main plate 21 centrally thereof for a purpose which will hereinafter appear. 10 28⁰ indicates my latch pin, which is formed inverted channel shape so as to engage with the notches 26² when the latch pin is raised. The inner end of the latch pin 28⁰ is provided with a semi-circular clamping portion 28¹¹ provided with lugs 28¹². 28² indicates a correspondingly formed portion provided with corresponding lugs adapted to be secured to the lugs 28¹² and portions 28¹¹ and 28¹² extending around the vertical bar 1' of 15 the gate 1 so as to be clamped thereto. By this means the latch pin may be adjusted vertically to any desired position upon the gate.

I will now describe the mechanism by 25 which the gate is locked in the open position. The lower end of the bar 4 is provided with an extension 4¹². 28 indicates a bar, which is secured to the extension 4¹² and extending at right angles to the normal position of the 30 gate beneath the level of the lower bar of the gate. Each end of the bar 28 is provided with lugs 28^x extending inwardly toward the gate between which a latching piece 28' is swung upon a pin 28², the latching piece being provided with a normally vertically extending portion 28³ and a horizontally extending portion 28⁴. The swinging movement of the latch piece 28' is limited by the pins 28⁵ and 28⁶. 28⁷ indicates 35 a lug extending outwardly from the opposite side of the bar 28 and provided with an upwardly inclined upper edge 28⁸. When the cord 17 is pulled as above described to open the gate and prior to the gate swinging 40 to the open position the latch pin 28 is carried upward between the vertical plate 27 and the swinging catch 26 until it is carried clear of the top of such catch. Should, however, the cord be released before the latch 45 pin arrives at the top of the swinging catch 26 the channeled lower face of the pin will engage with one of the notches 26² and prevent its return. By a further pull upon the cord 17 the pin is carried over the top of the 50 swinging catch and the gate swings to the open position. As it arrives at the open position the lower bar of the gate engages the upwardly projecting portion 28³ of the swinging catch 28' swinging the catch over 55 so as to engage with the pin 28⁶ which limits its movement. The lower bar of the gate passes over this catch which then drops by gravity to its normal position and then 60 engages the inclined edge 28⁸ of the lug 28⁷ riding upwardly thereon thereby tending to 65

elevate the gate bodily and thereby take up the jar, which will be consequent to the gate being suddenly stopped as it arrives at the open position. When the cord 18 is pulled in order to close the gate as has been before 70 described the gate is tilted in the usual manner by carrying the hinge connections out of alinement. By such tilting movement the lower bar of the gate is carried over the top of the upwardly projecting portion 29³ of the 75 catch 28' enabling it to swing to the closed position. As the gate arrives at the closed position the hinge pin passes between the horizontal plate 24 and the swinging catch 26, the swinging catch being lifted by the 80 latch pin engaging the outer face of the lower inclined portion of the swinging catch 26. As the latch pin passes the end of this swinging catch the swinging catch drops again on to the plate 24, the pin then engaging the upwardly inclined surface forming the inner face of the catch 25 riding upward thereon and thereby taking up the jar. 85

In order to prevent the gate being lifted over the latch by hand in the wrong direction when the dog is caught I have provided the plate 27 hereinbefore described extending from the main plate 21 of the latch. By this means it will be readily seen that when the gate is operated to open in either one 90 direction or the other the latch pin will be moved in the latch to the corresponding side of the latch and against the corresponding member 25 or 26 and is then lifted so that if anybody should attempt to then lift the gate 95 and force it in the wrong direction the latch pin will contact with the vertical plate 27 preventing its movement over to the other side of the latch and over the wrong side thereof. 100

In order to stiffen the bar 28 I have provided an angle bar 30, the ends of which are secured to the bar 28 in proximity to each end thereof, the center or arched portion of the angle bar 30 passing around to the opposite or outer side of the post 2, the bolt 4' passing through this center portion thereby holding the bar 28 rigidly in position. 110

From this description it will be seen that I have devised a very simple form of operating mechanism for gates which are automatically operated to open and close by means of the upper and lower hinge connections being carried out of alinement and in which simple means are provided for adjusting the gate support and latch support so as to compensate for any sag in either one of the gate posts and providing a device which may be readily attached to any form of iron gate and easily adjusted to the desired position. 115

It will be understood that the gate does not leave the latch simultaneously with the dog, the gate catching in the teeth 6⁴ but leaves the latch when the movement is carried a little farther, that is to say, at the 120 125 130

same time the projections 10⁴ and 10⁵ of the upper hinge strike the corresponding face of the boss 4⁷. This action applies both to the opening and closing operation of the 5 gate.

What I claim as my invention is:

1. In a farm gate, the combination with the gate post and lower hinge of the gate, of a vertically turnable shaft having an arm 10 intermediately of its length carrying the upper hinge pin and having an oppositely turned upper end, means for rotating the shaft from a distance, and means co-acting with the turned upper end for holding the 15 shaft in the turned position.

2. In a farm gate, the combination with the gate post and gate and the lower hinge of the gate, of a vertical turnable shaft carried by the gate post having a horizontally 20 turned upper end, a swinging dog carried by the horizontally turned end of the shaft and having a lateral tooth-engaging projection having a double engaging edge, a co-acting arc-shaped member carried by the 25 post, and having face-gear sections at each end, an intermediate gearless portion adapted to receive the dog and allow it to hang freely in the intermediate position, an arm extending from the turnable shaft, a hinge 30 connection between the end of the arm and the gate, and means operated remote from the gate for turning the shaft to carry the gate hinge connections out of vertical alinement.

3. In a farm gate, the combination with the gate post and gate and the lower hinge of the gate, of a vertical turnable shaft carried by the gate post, an arm extending therefrom, a hinge connection between the 35 end of the arm and the gate, a rectangular boss located in a stationary position and forming a bearing for the lower end of the turnable shaft, lugs extending laterally 40

from the hinge connection adapted to engage the front face of the rectangular boss 45 when the gate is operated to open and the side face of the post when the gate is operated to close.

4. In a farm gate, the combination with the gate post and gate, of a bar having a 50 cross slot at one end, a hinge connection between each end of the bar and the gate, means for pivotally mounting one end of the bar upon the gate post, a bolt extending through the slot of the bar into the gate 55 post, and nuts co-acting with the bolt to secure the bar in the adjusted position.

5. In a farm gate, the combination with the gate post and gate, of a bar spaced apart from the gate post, a hinge connection between the bar and the gate, bolts extending through the ends of the bar and the gate post, and nuts on each bolt at each side of the bar and at each side of the gate 60 post.

6. In a farm gate, the combination with the gate post and supporting members spaced from the gate post, a gate and a hinge connection between the gate and the supporting member, of a bar extending at right angles 70 to the gate and carried by the aforesaid supporting member, latch devices carried by the end of the bar adapted to secure the gate in the open position, a bracing bar connected at each end of the right angular bar 75 and extending around the gate post, a bolt extending through the hinge support, gate post and bracing bar, and nuts located on the bolt at each side of the support and at each side of the gate post at the inside of 80 the gate post and at each side of the bracing bracket.

CHARLES LUSH.
